UNITED STATES PATENT OFFICE.

JOHN D. BELANGER, OF CHICAGO, ILLINOIS, ASSIGNOR OF ONE-HALF TO GEORGE RACKY, OF CHICAGO, ILLINOIS.

WRENCH.

1,150,094.

Specification of Letters Patent. Patented Aug. 17, 1915.

Application filed November 27, 1914. Serial No. 874,288.

To all whom it may concern:

Be it known that I, JOHN D. BELANGER, a citizen of the United States, and a resident of the city of Chicago, in the county of Cook and State of Illinois, have invented a certain new and useful Improvement in Wrenches; and I do hereby declare that the following description of my said invention, taken in connection with the accompanying sheet of drawings, forms a full, clear, and exact specification, which will enable others skilled in the art to which it appertains to make and use the same.

My invention relates generally to improvements in wrenches, and it consists, essentially, in the novel and peculiar combination of parts and details of construction, as hereinafter first fully set forth and described and then pointed out in the claims.

20 My invention relates generally to wrenches and has for its object the construction of an adjustable wrench of a convertible type adaptable for use both as a monkey wrench and as a pipe wrench.

25 In the drawings already referred to which serve to illustrate my said invention more fully, Figure 1 is an elevation of a wrench constructed in accordance with the present invention. Fig. 2 is a longitudinal section 30 thereof taken on the line 2-2 of Fig. 1. Fig. 3 is an elevation of the jaws of the wrench, taken upon the opposite side thereof to Fig. 1. Fig. 4 is a perspective view of the movable jaw of the wrench.

35 Like parts are designated by corresponding characters or symbols of reference in all the figures of the drawings.

Reference being had more particularly to the drawings, 10 indicates the wrench shank 40 provided at its upper terminal with a transverse stationary jaw 11 and at its lower terminal with a handle 12. The body of this shank is flattened along two of its sides and provided with the threads 13 on the opposite side thereof, said threads being broken or mutilated as illustrated in Fig. 2. The threads, however, are continuous so that a nut operating thereon could, by its rotation, be caused to travel the length of the shank 10.

50 A casing 14 is mounted for reciprocation upon the shank 10 and is rectangular in cross section, so that the sides of said casing rest flush against the flat or smooth sides of the shank 10. This casing is hollow and 55 the walls thereof are pierced by the orifice

15 adjacent to the shank 10 and to the lower terminal of the casing 14, to receive the knurled nut 16 which is threaded upon the shank 10 and rotatably mounted in the orifice 15. It will be seen that as the nut 16 is rotated upon the shank 10 the threaded engagement thereof with the thread 13 of said shank will cause the casing 14 to be moved to and from the head 11 dependent upon the direction of the rotation of the nut 16.

A movable jaw 17 is pivoted in the upper end of the casing 14 by means of a transverse extension 18 formed thereon which extends into the casing 14 and is pierced by a pin 19. This pin 19 is arranged adjacent to the shank 10 and is so mounted that the lower terminal of the extension 18 rests in close proximity to the shank 10 and acts as a guide for said shank.

75 A lenticularly bent leaf spring 20 is attached to the lower end of the extension 18 and at its free terminal bears against the shank 10. The lenticular construction of this leaf spring is such that the movement 80 of housing 14 along the shank 10, which carries the jaw 17 therewith, does not cause the terminal of said leaf spring to be engaged by the threads 13 on said shank. The leaf spring 20 being interposed between the 85 extension 18 of the jaw 17 and the shank 10 forces said jaw 17 away from the shank 10 to assume the position illustrated in full lines in Fig. 2. When the movable jaw 17 is in this position, the wrench is adapted for 90 use as a pipe wrench.

In order, however, to convert this wrench into a square faced or monkey wrench, it is necessary to swing the jaw 17 above its pivotal point against the action of the spring 95 20 to assume the position illustrated in dotted lines in Fig. 2, in which position the jaw 17 rests parallel to the jaw 11 instead of at an acute angle thereto. To accomplish this the face of the casing 14 is pierced by 100 a longitudinal slot 21 in which reciprocates a stem or button 22. This stem or button carries a stem or slide 23, the upper terminal of which is provided with a cam surface 24. When the slide is in the position illustrated in full lines 22 the jaw 17 assumes a position, under the influence of the spring 20, at an acute angle to the jaw 11. If on the contrary, however, the slide 23 is reciprocated vertically to the position illus- 105 110

trated in dotted lines in Fig. 2 the cam surface 24 thereof contacts with the extension 18 of the jaw 17, and swings the same about its pivot 19. This causes the extension 18 to rest parallel to the casing 14 and the jaw 17 to rest parallel with the jaw 11. The slide is of such proportion that when it is elevated it rests flush against both the extensions 18 and the adjacent face of the casing 14, and is frictionally held in this position.

The upper edge of the casing adjacent to the jaw 17 is provided on each side thereof with the upwardly projecting guiding surfaces 25, which coöperate with the curved guides 26 formed on each side of the jaw 17. As the jaw 17 swings to its adjusted positions the guides 26 thereof operate on the projections 25 and insure stability to the entire structure.

While herein I have described the preferred method of practising my invention, I may make changes in details thereon without departing from the spirit or scope of my invention.

Having thus fully described my invention I claim as new and desire to secure to myself by Letters Patent of the United States:—

30 1. A wrench including a shank possessed of a stationary jaw at one end, a hollow, movable casing embracing said shank, the forward edges of said casing on each side of said shank being of vertical arcuate contour, 35 the top of said casing at the front edge thereof being likewise arcuate and a continuation of said arcuate edges, a jaw pivoted within said casing possessing depending side wings embracing said shank along its sides thereof, said wings being arcuate on their rear vertical edges, engaging the arcuate edges of said casing, there being an arcuate face on the rear of said jaw contacting with the upper arcuate edge of said casing, and a leaf spring constructed to normally maintain said jaw against the said 45 upper edge of said casing, and slid able means in said casing adapted to enforce downward movement of said pivoted jaw, said means including a slideable bar located within said casing contiguous with the upper, inner face thereof, there being a longitudinal slotted opening through the top of said casing, a pin passing through said slot and engaging said slideable member, and means on said pin preventing its dropping through said slot.

45 2. A wrench including a shank possessed of a stationary jaw at one end, a hollow, movable casing embracing said shank, the forward edges of said casing on each side

of said shank being of vertically arcuate contour, the top of said casing at the front edge thereof being likewise arcuate and a continuation of said arcuate edges, a jaw 55 pivoted within said casing possessing depending side wings embracing said shank along its sides thereof, said wings being arcuate on their rear vertical edges, engaging the arcuate edges of said casing, there being an arcuate face on the rear of said jaw contacting with the upper arcuate edge of said casing, and a leaf spring constructed to normally maintain said jaw against the said 60 upper edge of said casing, and slideable means in said casing adapted to enforce downward movement of said pivoted jaw.

3. A wrench including a shank possessed of a stationary jaw at one end, a hollow, movable casing embracing said shank, the 70 forward edges of said casing on each side of said shank being of vertical arcuate contour, the top of said casing at the front edge thereof being likewise arcuate and a continuation of said arcuate edges, a jaw 75 pivoted within said casing possessing depending side wings embracing said shank along its sides thereof, said wings being arcuate on their rear vertical edges, engaging the arcuate edges of said casing, there being 80 an arcuate face on the rear of said jaw contacting with the upper arcuate edge of said casing, and a leaf spring constructed to normally maintain said jaw against the said upper edge of said casing, and slideable 85 means in said casing adapted to enforce downward movement of said pivoted jaw, said means including a slideable bar located within said casing contiguous with the upper, inner face thereof, there being a longitudinal slotted opening through the top of said casing, a pin passing through said slot and engaging said slideable member, and means on said pin preventing its dropping 90 through said slot.

95 In testimony whereof I have hereunto set my hand in the presence of two subscribing witnesses.

JOHN D. BELANGER.

In the presence of—
MARTIN NELSON,
C. S. STARK.
